The A. C. Gilbert Company, New Haven, Conn.,
a corporation of Maryland

Application June 20, 1946, Serial No. 677,932

17 Claims. (Cl. 46—9)

1

This invention relates to apparatus of the type and for the purpose set forth in my two copending applications, Serial No. 409,056, filed August 30, 1941, now Patent Number 2,461,664 and Serial No. 457,547, filed September 7, 1942, and now abandoned, such apparatus being particularly designed to be contained in restricted spaces such as a hollow miniature toy building or carried in hollow miniature rolling stock of a toy electric train for causing the emission of visible smoke-like or steam-imitating fumes from the building or from the locomotive of a toy train in puffs of realistic appearance and in conjunction with sound effects effectively imitating the puffing noises of a steam engine. Certain features of the invention disclosed but not claimed herein are claimed in my copending application, Serial No. 691,848, filed August 20, 1946.

The present improvements are directed particularly to compacting and operatively associating in a unitary structure noise producing and fume producing elements comparable to those which in my copending applications referred to above are spaced apart on separate pieces of toy railroad rolling stock, heretofore located, say, partially in a toy locomotive and partially in its tender or some other car of a toy train.

An object of the present improvements as relating to a toy train is to confine the sight-and-sound puffing apparatus to the interior either of a pseudo steam puffing toy locomotive alone or of the tender alone, the present disclosure illustrating for example the latter disposition of the apparatus, and by modification the former.

A related object is structurally to organize an electrically powered sound and fume producer on a common sub-assembly base so that it is installable and operates as a unit in a hollow toy or in any single piece of toy rolling stock and can be removed therefrom as a unit without operatively disassociating its working parts.

A further object is to unitize a sound producer and a smoke generator in a sub-frame comprising a single integral casting that may be compartmented to take the place of separated and spaced hollow structures which heretofore in this type of apparatus have been connected by fluid conduit for giving fluid communication therebetween. By the present improvements the use of conduit or tubing for cooperatively relating a puffing sounder and a smoke generator is avoided.

Another object is to simplify and render more effective the smoke generator of my aforesaid copending applications.

10 2 A specific object is to replace the cylinder and plunger pump of my prior applications with a space saving and particularly efficient type of air pumping bellows that better serves a like purpose by producing a maximum cubical displacement of air in relation to a smaller overall space occupied by the expanding and collapsing bellows.

15 A further and particular object is to control the movements of a box type of bellows as distinguished from a fan type of bellows with a minimum complexity of bellows actuating mechanism and if desired free from friction producing guide means.

20 A still further object is to facilitate the refilling of the compartment containing a vaporizable liquid from which the fumes are derived by providing such compartment with a filler spout or passageway opening to the exterior of a hollow toy or toy railway car through preferably the top external wall thereof. If the toy be a steam operated logging station or the like or the locomotive of a toy train the open end portion of the filler spout may project a substantial length thereabove to give the appearance of a smoke stack.

25 30 Where this smoke stack idea is carried out, it is also within the concept of this invention to discharge the heat generated fumes directly into such smoke stack in such manner that a refilling charge of the vaporizable liquid poured or dropped into such smoke stack will pass by gravity to its proper containing chamber rather than into the fume generating chamber.

35 35 Successful embodiments of the invention by which the foregoing objectives may be attained are hereinafter described in detail with reference to the appended drawings wherein:

40 40 Fig. 1 shows a toy tender coupled to its locomotive and encasing a unified puffing sounder and fume puffer embodying the present invention.

Fig. 2 is a side view of the tender alone drawn on an enlarged scale with certain of the chassis and casing parts shown partly in section.

45 45 Fig. 3 is a plan view of the tender of Fig. 2 taken in section on the planes 3—3 in Fig. 2.

Fig. 4 is a still further enlarged plan view of the puffing sounder and fume generator with its top walls partially broken away exposing certain internally compartmented construction.

50 50 Fig. 5 is a view taken mostly in section on the plane 5—5 in Fig. 4 looking in the direction of the arrows.

Fig. 6 is a view taken in section on the plane 6—6 in Fig. 5, looking in the direction of the arrows.

Fig. 7 is a perspective view of the apertured sounding plate removed from the assemblage of Figs. 4 and 5.

Fig. 8 is an enlargement of a portion of Fig. 6 showing more clearly in detail the anchorage for the heating wire and electrical connections thereto.

Fig. 9 is a perspective view showing partly in section one of the wheeled trucks on which the tender rides.

Fig. 10 is a diagram of electrical connections.

Fig. 11 shows a modified arrangement of the filling inlet leading to the liquid magazine.

Fig. 12 is a plan view of a portion of the puffing and sounder unit drawn on a larger scale than in Fig. 4 with the superstructure partially broken away to expose a manually operable circuit controller and a still further modified form of filler inlet for the liquid magazine.

Fig. 13 is a detailed view of the circuit controller taken in section on divergent planes 13-13 in Fig. 12 looking in the direction of the arrows.

Fig. 14 shows the unit of Fig. 12 installed in the tender of Fig. 2 and in the process of being recharged with a supply of fume producing liquid and shows part of the structure sectioned on plane 14-14 in Fig. 12.

Fig. 15 shows about twice actual size the compressible refilling capsule of Fig. 14 in the sealed form in which it is merchandised before being used as in Fig. 14.

Fig. 16 shows a still further modification of the filler inlet and fume outlet incorporated in a toy locomotive wherein the liquid filler inlet projects from the locomotive like a smoke stack and is made to emit the smoke-like fumes that are derived from the liquid.

The toy locomotive and tender of Fig. 1 is shown in $\frac{3}{4}$ actual size of the so-called H-O gauge toy railroad whose tracks measure $\frac{5}{8}$ inch between rail centers in the two-rail type of track here illustrated. It is therefore apparent that in the interior of such very small toy cars or single units of toy rolling stock, such as the tender 13, very little space is available to contain apparatus capable of successfully producing sound and smoke effects. This stringent space restriction has heretofore necessitated a distribution of the sound and smoke producing apparatus between more than one piece of the toy rolling stock, such as between the locomotive and its tender.

I have devised an organization of the essential components of a sound and smoke producing apparatus which enables them, together with an electric power motor by which they are operated, to be contained within as small a space as $\frac{1}{8}$ square inch by $3\frac{3}{8}$ " long. This enables them all to be housed within the style and size of tender that is conventional in H-O gauge trains.

For the purpose of constructing the jointly operative sound and smoke apparatus as a sub-assembly unit that can be built complete as such, and tested in fully operative form before being installed in the car of a toy train, all parts of such unit are mounted preferably on a common base plate 15 which comprises a rigid die casting that may be secured removably to the chassis 16 of tender 13 by holding screws 17 in a position accurately determined by downward projecting dowels 18 cast on the base plate 15 and fitting holes or sockets in the tender chassis.

Base plate 15 has cast integrally therewith an upstanding wall 22 having laterally projecting cast bosses 23 against which is mounted the D-type laminated stator 24 of motor 14 carrying the

field winding 25. This stator is secured against frame bosses 23 by long holding screws 26 having threaded engagement with the boss 23 and passing through the stator as well as through a bearing plate 28 of insulative material and through tubular spacers 27 holding the latter in rigid relation to the stator.

Embedded in insulative plate 28 there is a metallic bushing that affords bearing for one end 10 of the motor armature shaft 32 whose opposite end has a bearing 29 in the frame wall 22 and terminates outside of this frame wall in a worm 33. The motor shaft 32 carries a three-pole armature having respectively three electric windings 35. It also fixedly carries the commutator 36 whose radial face is contacted by brushes 37 resiliently pressed toward said commutator face and fed with electric current by the conductive leaf springs 38 that are mounted in insulated relation on bearing plate 28, there being two brushes 37 on diametrically opposite sides of armature shaft 32.

Thus motor 14 through its shaft worm 33 is constantly in mesh with and able to rotate a worm gear 39 which is pivotally mounted to turn about a vertical axis on the top of a stationary bearing post 40 which post may be cast integrally with base plate 15 or mounted fixedly thereon. Worm gear 39 is retained by a shoulder screw 41 which serves as its pivotal bearing. Worm gear 39 carries a crank pin 42 herein shown as a removable screw stud having threaded engagement therewith. Altogether the foregoing parts constitute a speed reduction gear serving as power transmitting mechanism.

There will next be described the compact organization of a unified sound and fume producer which I have devised in a form susceptible of being contained in the small remaining space 40 measuring $\frac{1}{8}$ " square by $1\frac{1}{8}$ " long. The problem of so doing can not be met merely by making formerly proposed forms of apparatus smaller because to do so would reduce to an unsatisfactory degree the volume of air capable of being pumped for producing the desired smoke and sound effects.

I have combined a resonance box or sound chamber 45, a smoke storing compartment 46 and a liquid containing refillable magazine 47 in an integral hollow casting forming a box-like enclosure separate from base casting 15 and indicated as a whole by the numeral 49. This casting has side walls 50, an end wall 51 comprising external walls, a vertical partition wall 52 and a horizontal partition wall 53. The shape of this casting leaves compartments 45, 46 and 47 only partially housed by walls 51, 52 and 53. These compartments, so far as casting 49 alone is concerned, remain open at the bottom or at the top. In assembly, however, the open bottoms of sound chamber 45 and magazine 47 are leak-proof because closed liquid tight by the mounting of casting 49 on base plate 15 with an intervening, joint-sealing gasket 54. Casting 49 is held by four fastening screws 55 having threaded engagement with internal bosses on walls 51 and 52 and passing through clearance holes in base plate 15. The open tops of sound chamber 45 and compartment 46 are completely sealed liquid tight by a cover plate 56 of insulating material secured against the top of casting 49 by four holding screws 57 having threaded engagement with internal bosses on walls 51 and 52.

As best shown in Fig. 4 the side walls 50 of casting 49 are provided with vertically extending

longitudinally grooved ribs 62 which retain the lateral edges of sounder plate 63 so that this plate can be removed from casting 49 by sliding it edgewise out of the grooves in ribs 62 when cover plate 56 is removed from casting 49. With the exception of an aperture 64 in plate 63 the plate forms a pneumatically sealed closure for sound chamber 45. This chamber nevertheless has a measure of fluid communication with the smoke storing compartment or reservoir 46 through a tiny opening 65 in partition wall 52 that enables pulsations of air pressure in sound chamber 45 to be transmitted to the smoke reservoir 46. It is new with this invention to do away with the use of connecting tubing for affording such fluid communication. Aperture 64 is lipped at 66 to cause sound producing diversion of a jet of air 69 impelled by bellows 70 through a jet orifice 71, as best shown in Figs. 4, 5 and 7.

Bellows 70 constitute a reciprocative pump or pneumatic blower and is of the box type familiar in accordion and like constructions specially adapted for the present use to afford a maximum ease and capacity of voluminous air displacement by the slight amount of bellows movement that can be accommodated within the small confines of cubical space here available. It will be understood however that where space permits, it is within the scope of this invention to substitute a fan type of bellows or any other form of air pump that proves capable of sufficient volume of air displacement for the purposes desired. I have discovered that a box type of bellows not only displaces more air per linear extent of movement than does a fan type or hinged type of bellows but affords a more abrupt effect on the air when it starts to expel same. This is important for producing the kind of aerodynamic effect best suited to realistically imitating the puffing sounds and fume behavior of steam engine exhaust action.

Bellows 70 comprises a stiff stationary anchor plate 72 and a stiff head plate 73 that reciprocates broadside. Movable plate 73 is connected to stationary plate 72 by a foldably collapsible tubular wall 74. For minimum resistance in the bellows action I have found it advantageous to make the flexible bellows walls 74 of very thin rubberized fabric such as the material commercially known as Terson bellows cloth or Vinylite coated on a base of HH balloon cloth. Fabric 74 has its tubular end margins cemented in air tight relation to the periphery of plates 72 and 73 and is creased symmetrically to determine its lines of flexure as plate 73 approaches and recedes from the plate 72.

The stationary or anchored bellows plate 72 is fixedly mounted against the upright surface of a support apron 75 that forms a part of casting 49, by a removable fastening bolt 76 having threaded engagement with plate 72. Bolt 76 contains the jet orifice 71 extending entirely therethrough and giving the interior of bellows 70 fluid communication with the space 68 between apron 75 and sounder plate 63 which space opens freely to ambient air both at its lower sides and through an aperture 67 in base 15 and chassis 16. To afford the pneumatic efficiency or straightaway direction of air flow through the jet orifice 71, sound aperture 64 and smoke impulsive opening 65 are coaxial and comprise short passageways for the air impelled by the jet in contrast to long stretches of flexed rubber tubing heretofore proposed for giving fluid communication between an air jet, a sound chamber and a smoke reservoir.

The movable head plate 73 of the bellows has fixed thereon by rivets 79 an actuating projection in the form of bar 80 containing in its free end a transverse elongated slot 81 that is pivotally and slidably engaged by the aforesaid crank pin 42 that revolves with worm gear 39. This causes the bellows head plate 73 to be reciprocated toward and away from the stationary bellows plate 72. The elongation of slot 81 increases the pause of bellows head 73 when positioned as in Fig. 3 between each reversal of its reciprocative movements, and reduces the degree of annular inclination to which head 73 is forced in relation to head 72 when crank pin occupies its position shown in dash lines in Fig. 4.

In much the same way as in my copending applications hereinbefore referred to, smoke is generated in the superimposed compartment 46 by the electrical heating and vaporization of a replenishable supply of liquid that is convertible into fumes and derived from the underlying storage compartment or magazine 47. This fume source liquid, usually of oily nature, is absorbed and led upward by capillary attraction from magazine 47 through a loop of fibrous wicking 82 best shown in Figs. 5 and 6. This wicking fills and passes through tight fitting holes in bosses 83 which serve to thicken the horizontal partition wall 53, at all other points serving to seal magazine 47 liquid tight and to isolate it from the smoke reservoir 46. This constitutes means to feed the fume source liquid or substance automatically from compartment 47 to compartment 46. A fine electrical resistance wire 84 is close-wound tightly about a horizontal stretch of the wicking 82 in compartment 46 and is anchored by being embedded in a solder core 88 filling the interior of eyelets 85 in the cover plate 56. Resistance wire 84 extends through this solder core and is soldered to binding posts 86 and 87 fastened against the outer surface of cover plate 56 by the heads of eyelets 85. This constitutes means to vaporize the fume source liquid in compartment 46.

The lower free ends 90 of wicking 82 intermingle in jumbled relation at the bottom of liquid magazine 47 in a manner efficiently to absorb and soak up from any portion of the magazine interior whatever content of vaporizable liquid there may be in the magazine. This supply of liquid is replenishable through a filler opening in coupling 91 which may comprise a tubular stud threading into the end wall 51 of casting 49 and having an intake or filler passageway 94 through it that is plugged at the outer or filler end by a removable screw 92 that threads into coupling 91 and prevents leakage of liquid because sealed by a gasket washer 93. Filler passage 94 is structurally isolated from compartment 46.

Outlet for smoke ejected from compartment 46 is through a nipple 95 threaded into the end wall 51 of casting 49 and on the outwardly projecting end of which is sleeved the detachable end of a rubber tube 96 which leads to and gives upward through the imitative smoke stack 97 of locomotive 12.

Base 15 of this unitary puffer is removably attached to the chassis 16 of the tender 13, or to the inside of any other hollow toy such as the toy locomotive 12 or a stationary toy trackside logging mill, by screws 17 whose location and arrangement are shown by broken lines in Figs. 2 and 3. These figures of the drawings also show the location on the unit base 15 of a manually operable electric switch, indicated as a whole by

100, for making and breaking the supply circuit through both the shunt related motor 14 and heating coil 84 in an arrangement of circuit connections diagrammed in Fig. 10. The diagram of Fig. 10, in conjunction with the cut-away view of the current collecting structure of one of the toy car trucks in Fig. 9, makes clear that each truck is equipped with insulative wheels 101 that roll on one of the two metallic track rails 102, 104 and with metallic wheels 103 which roll conductively on the other of said track rails. Since the conductive wheels of the two trucks run on respectively different track rails, as is represented in Fig. 10, electric current supplied through either of track rails 102 or 104 is returned to the other of these track rails through a split electric circuit containing in one branch the motor 14 and in the other branch the heating coil 84. Current is collected from rail 102 by wheels 103 and passes through the wheel axles 105, brush plate 106, brush spring 107, and truck pivot stud 108 to the switch 100 and thence divides between motor 14 and heating coil 84 and returns to track rail 104 through the pivot stud 108, brush spring 107, brush plate 106, axles 105 and conductive wheels 103 of the other truck. Thus both the motor and the heating coil derive their energizing current from track rails 102, 104.

The detailed construction of switch 100 appears more clearly in Figs. 12 and 13 wherein the casting of unit base 15 is shown to be hollowed upward at 109 affording cavities that make room for the connection of conductive wires respectively to a stationary switch contact 110 and to the pivot 112 of a swingable conductive switch contact arm 113 whose handle end 114 projects to the outside of tender 13 sufficiently to be manually accessible. The side edges of a notch 115 afford stops in either direction for the swinging movement of switch arm 113. Switch 100 is shown in circuit-making position by full lines in Fig. 12 wherein the broken lines indicate circuit-breaking position of this switch. The tender chassis 16 is topped by the usual removable casing 115 secured by screws 117 and contoured externally to imitate in miniature a load of coal piled up in the bin of the tender.

Fig. 11 shows a modification of the filler fitting 91 wherein the sealing of liquid in the magazine or storage compartment 47 is effected hydraulically by trapping it rather than by means of plug screw 92 and gasket 93. A nipple 118 which may be similar to nipple 95, is sleeved by the end of a flexible tube 119 whose other end is correspondingly sleeved over the interior end of a tubular inlet 120 formed on and opening through the top or roof wall 121 of the tender casing 116. The aperture through inlet 120 is internally threaded to be stopped by a plug screw 126 which is easily removable by hand so that a refilling charge of vaporizable liquid can be supplied to magazine 47 by dropping or pouring it into inlet 120 through the top wall 121 of the tender. However, plug screw 126 is not now normally necessary because the higher level of inlet 120 provides a hydraulic trap preventing escape of liquid from the storage chamber even when the latter is completely full. It has been mentioned hereinbefore that a cover wall 121 penetrated by inlet 120 might constitute the top wall of a locomotive 12 as in Fig. 16 or some other piece of toy train rolling stock, or might constitute the roof of a miniature toy building such as a trackside logging mill.

In Figs. 12, 14 and 16 an equivalent for filler inlet 120 is shown to consist of an internal boss 75

129 on wall 51 of box casting 49 containing a vertical intake or filler passage 130. In the enlarged top portion of passage 130 there is inserted a permanent filler funnel 131 which like inlet 120 may be plugged at its internally threaded top end by a removable thumb screw like 126. Fig. 14 shows the position that funnel 131 may assume in relation to the top wall 121 of tender casing 116.

Figs. 14 and 15 illustrate an economical, clean and convenient throw-away dispensing package in which charges of liquid may be merchandised for replenishing magazine 47. 136 is a gelatin capsule filled with the liquid 138 and whose walls are contoured to form an elongated dispensing nipple 137 which may be externally threaded to screw into, or may merely be loosely inserted in, filler funnels 131 of Fig. 14 or 131' of Fig. 16 hereinafter described. In the form merchandised, the tip end of the nipple 137 is sealed by continuity of the gelatin wall of the capsule as shown in Fig. 15. Because of the softness of the capsule wall the tip end of nipple 137 can be nipped off by the thumb nail of a person's hand and the passageway through the spout is so small in cross section in proportion to its length that the liquid contents of the capsule will not run out even if the open tip of the nipple is turned downward inasmuch as air cannot enter upward against the weight of the liquid that fills the nipple. However the capsule, having flexible walls, can be squeezed as shown in Fig. 14 as one would squeeze the sides of an oil can and this causes the liquid contents of the capsule to be discharged into the filler funnel with dispatch and in a clean way which avoids spilling or daubing of any of the oily liquid over external surfaces of the toy. When the tip of nipple 137 is externally threaded to screw into the internal threads of funnel 131 or 131' with a liquid tight fit before the capsule is squeezed, this form of refueling apparatus is absolutely spill proof.

Fig. 16 shows one of many possible structural arrangements whereby the smoke-like fumes that are discharged from reservoir 45 may be led preferably laterally into the upper open end portion of a modified filler funnel 131'. The flexible conduit 96' from nipple 95 is sleeved over a branch nipple 140 that communicates with the vertical passageway through the modified funnel 131'. Thus this funnel serves the combined function of filler inlet and smoke outlet enabling the liquid magazine 47 to be filled through the smoke stack 97 of locomotive 12 if the entire puffing unit is transferred from tender 13 to the hollow interior of locomotive 12 in such position that funnel 131' takes the place of smoke stack 97. The broken lines 131'' in Fig. 16 indicate an upward lengthening of stack 131' which will make it more realistic in imitating the appearance of a power plant smoke stack when projecting above the roof of a toy mill, factory or steam power plant in which my improved puffing unit may be installed. Also in the funnel or stack 131' of Fig. 16, the smaller bottom portion 141 of the passage may be threaded to receive the slender shanked screw 142 which has a long enough threaded bottom plug end to cause its top slotted end to protrude accessibly from stack 131' when it is sufficiently unscrewed. The presence of stopper screw 142 prevents leakage of liquid fuel 138 out of magazine 47 in case the locomotive should overturn but in no way interferes with the discharge of the smoke-like, engine puffing fumes out of locomotive stack 131' or 131''. Intake or filler passage 130 in Fig. 16 extends downward past the compartment 46 and

leads the fuel liquid downward by gravity while the exhaust passage 96 merges laterally into the intake or filler passage at a relatively high point therein.

In operation, whether the toy train of which tender 13 is a part is running along its track or standing still, if manually operable switch 100 is closed, heater 84 will constantly vaporize liquid fuel 133 in compartment 46 as such fuel is drawn up to it from compartment 47 through wicking 82. The resulting fumes will dwell in compartment 46 until ejected therefrom by intermittent air impulses driven through the hole 65 by the impacts of jets of air 69 forced out of bellows 70 and acting through aperture 64 on the partially imprisoned body of air in sound chamber 45 as motor 14 reciprocates the bellows head 73. The thus ejected fumes will leave smoke stack 97 or 131' of the locomotive in realistic puffs accompanied synchronously by puffing sound produced by the effect of sounder lip 66 on the intermittent jets of air.

When magazine 47 needs replenishing, the screw plug 92 or 126 or 142 may be removed from its inlet and use may be made of the capsule 136 by nipping off the sealed tip of its nipple 137, placing such nipple in the filler opening 94, 120, or funnels 131, 131' and squeezing the sides of the capsule together. Capsules having externally threaded nipples may be screwed into the filler inlet or into said funnels before squeezing them to insure against leakage while filling.

Thus there is afforded a spill-proof refuelable realistically performing puffing toy that is housable in extremely small spaces, especially suited to the narrow elongated shape of toy railway rolling stock while capable of producing voluminous smoke effects accompanied by realistic puffing sounds.

The appended claims are directed to and intended to cover not only the particular embodiments herein chosen to illustrate the invention but also all commonly known substitutes therefor and alternatives thereof.

I claim:

1. A rechargeable fume generating unit of miniature size for containment in the restricted space of hollow miniature toys, comprising in combination with an external wall of the toy, a box-like enclosure within said toy partitioned to divide said enclosure into underlying and superimposed neighboring compartments, means operative to feed a fume source substance automatically from said underlying compartment to said superimposed compartment, means operative to vaporize said substance in said superimposed compartment, and an intake passage extending between said underlying compartment and said external wall of the toy and having an inlet receptive to said substance opening through said wall at a level higher than both of said compartments, said passage extending from said inlet downward past said superimposed compartment thereby to receive a replenishing charge of said substance and lead the same by gravity from said inlet downward past said superimposed compartment into said underlying compartment.

2. A rechargeable fume generating unit as defined in claim 1, in which the said intake passage is located within and extends through said box-like enclosure.

3. A rechargeable fume generating unit as defined in claim 1, in which the said toy comprises a miniature wheeled vehicle simulating a toy locomotive, and the said inlet is fashioned ex-

ternally to simulate the smoke stack of said locomotive.

5. A rechargeable fume generating unit as defined in claim 1, in which the said enclosure incorporates a hollow partitioned casting containing said compartments and also containing said intake passage in structurally isolated relation to said compartments.

10 5. A toy locomotive comprising in combination, an imitative smoke stack, means to convert a liquid into fumes, a passageway guiding said liquid to said means inward through said smoke stack, and a passageway guiding said fumes from said means outward through said smoke stack.

15 6. A toy pseudo steam puffing locomotive including in combination with an imitative smoke stack atop said locomotive, neighboring compartments within said locomotive the first of which is constructed to be leakproof with respect to liquid contained therein, means to feed a fume source liquid automatically from said first to a second one of said compartments, means to vaporize said liquid automatically into fumes in said second compartment, and a filler passage leading to said first compartment and opening externally of said locomotive through said smoke stack.

20 7. A toy pseudo steam puffing locomotive including in combination with an imitative smoke stack atop said locomotive, neighboring compartments within said locomotive the first of which is constructed to be leakproof with respect to liquid contained therein, means to feed a fume source liquid automatically from said first to a second one of said compartments, means to vaporize said liquid automatically into fumes in said second compartment, and a filler passage leading to said first compartment and opening externally of said locomotive through said smoke stack, together with a fume exhaust passage leading from the said second compartment and opening outward of said locomotive through said smoke stack.

25 8. A toy pseudo steam puffing locomotive as defined in claim 7, wherein the said filler passage extends downward from the said smoke stack to the said first compartment, and the said fume exhaust passage merges laterally into said filler passage whereby the said fume source liquid received through said smoke stack will pass to the said first one of said compartments much more readily than to the said second one of said compartments.

30 9. A single unit of miniature toy rolling stock equipped to run on electrified toy track rails, incorporating in combination with a unitary rigid wheeled chassis, a source of smoke-like fumes carried on said chassis, a fume impulsing apparatus carried on said chassis cooperatively associated with said fume source in a manner to cause puffs of fumes derived therefrom to depart from said unit of rolling stock, a producer of pseudo steam puffing sounds carried on said chassis including a pneumatic blower, an electric motor carried on said chassis deriving current from said track rails, mechanical connections enabling said motor to operate said blower, and common current collecting means carried on said chassis electrically connected to energize both said impulsing apparatus and said source of smoke-like fumes.

35 10. A single unit of toy rolling stock equipped to run on electrified toy track rails, incorporating in combination with a unitary rigid wheeled chassis, a source of smoke-like fumes carried on

said chassis, a fume impulsing apparatus carried on said chassis cooperatively associated with said fume source in a manner to cause puffs of fumes derived therefrom to depart from said unit of rolling stock, a producer of pseudo steam puffing sounds carried on said chassis including a pneumatic blower, an electric motor carried on said chassis deriving current from said track rails, and mechanical connections enabling said motor to operate said blower, said sound producer comprising a rigid box-like structure, and said pneumatic blower comprising an accordion type of bellows having one of its ends fixed externally on said box-like structure and its other end impellably related to said mechanical connections.

11. A single unit of toy rolling stock equipped to run on electrified toy track rails, incorporating in combination with a unitary rigid wheeled chassis, a source of smoke-like fumes carried on said chassis, a fume impulsing apparatus carried on said chassis cooperatively associated with said fume source in a manner to cause puffs of fumes derived therefrom to depart from said unit of rolling stock, a producer of pseudo steam puffing sounds carried on said chassis including a pneumatic blower, an electric motor carried on said chassis deriving current from said track rails, and mechanical connections enabling said motor to operate said blower, said sound producer comprising a rigid box-like structure, and said pneumatic blower comprising an accordion type of bellows having one of its ends fixed externally on said box-like structure, and said mechanical connections including a speed reduction gear driven by said motor and a power transmitting mechanism constructed and arranged to enable said gear to impel the other end of said bellows in both of opposite directions.

12. A single unit of toy rolling stock equipped to run on electrified toy track rails, incorporating in combination with a unitary rigid wheeled chassis, a source of smoke-like fumes carried on said chassis, a fume impulsing apparatus carried on said chassis cooperatively associated with said fume source in a manner to cause puffs of fumes derived therefrom to depart from said unit of rolling stock, a producer of pseudo steam puffing sounds carried on said chassis including a pneumatic blower, an electric motor carried on said chassis deriving current from said track rails, and mechanical connections enabling said motor to operate said blower, said sound producer comprising a rigid box-like structure, and said pneumatic blower comprising an accordion type of bellows having one of its ends fixed externally on said box-like structure, and said mechanical connections including a worm driven by said motor, a worm wheel driven by said worm, a crank pin revolved by said worm wheel, and an actuating projection on the other end of said bellows engaged by said crank pin in a manner to be impelled in both of opposite directions by revolving movement of the latter.

13. A single unit of toy rolling stock equipped to run on electrified toy track rails, incorporating in combination with a unitary rigid wheeled chassis, a source of smoke-like fumes carried on said chassis, a fume impulsing apparatus carried on said chassis cooperatively associated with said fume source in a manner to cause puffs of fumes derived therefrom to depart from said unit of rolling stock, a producer of pseudo steam puffing sounds carried on said chassis including a pneu-

matic blower, an electric motor carried on said chassis deriving current from said track rails, and mechanical connections enabling said motor to operate said blower, said sound producer comprising a rigid box-like structure, and said pneumatic blower comprising an accordion type of bellows having one of its ends fixed externally on said box-like structure, and said mechanical connections including a worm driven by said motor, a worm wheel driven by said worm, a crank pin revolved by said worm wheel, and an actuating projection on the other end of said bellows having an elongated slot pivotally and slidably engaged by said crank pin in a manner to cause 10 said other end of the bellows to be impelled in both of opposite directions by revolving movement of said crank pin with a pause at each reversal of the responsive bellows movement.

14. Toy refueling apparatus for replenishing a liquid consuming pseudo-steam puffing unit for toys, comprising in combination with a magazine within the toy for storing a fume source liquid, a filler opening in the toy affording entrance of said liquid to said magazine, and a sealed capsule containing a charge of said liquid, said capsule being separable from the toy and having walls contoured to form a nipple having a tip closed by the material of said walls, said walls of the capsule being sufficiently flexible to yield 25 inward to squeezing pressure of the operator's fingers and soft enough to enable said closed tip of the nipple to be nipped off by pressure of the operator's thumbnail thereby to afford outlet for said liquid through said nipple when the latter is 30 applied to said filler opening in the toy.

15. Spill-proof toy refueling apparatus as defined in claim 14, in which the said filler opening is internally screw threaded and the said nipple is externally screw threaded in a manner to be 40 screwed into said threaded filling opening with a liquid tight screw fit.

16. A single unit of miniature toy rolling stock equipped to run on and collect current from electrified toy track rails, incorporating a narrow elongated rigid wheeled chassis, said chassis carrying a pseudo steam puffing unit comprising in straight alignment lengthwise of said chassis and in cooperative combination, a source of smoke-like fumes, a producer of imitative steam puffing sounds, a single reciprocative pump all in mutual fluid communication through coaxial passageways, and an electric motor powered from said track rails and connected to operate said pump.

17. A single unit of miniature toy rolling stock as defined in claim 16, together with an integral casting housing the said source of smoke-like fumes and the said producer of steam puffing sounds.
